UNITED STATES PATENT OFFICE

RUDOLPH BERLINER, OF LOS ANGELES, CALIFORNIA

DESIGN FOR A COMBINED TABLE AND RACK

Application filed October 28, 1931. Serial No. 41,552. Term of patent 3½ years.

To all whom it may concern:

Be it known that I, RUDOLPH BERLINER, a citizen of the United States, residing at Los Angeles, in the county of Los Angeles and State of California, have invented a new, original, and ornamental Design for a Combined Table and Rack, of which the following is a specification, reference being had to the accompanying drawings, forming a part thereof.

Figure 1 is a front elevation of a combined table and rack showing my new design.

Figure 2 is a plan view thereof.

I claim:

The ornamental design for a combined table and rack as shown.

RUDOLPH BERLINER.
